EXPANSIBLE BAND OR BRACELET

Louis Edmond Valcourt, East Providence, R. I., assignor to Kestenman Bros. Mfg. Co., Providence, R. I., a corporation of Rhode Island

Application January 11, 1949, Serial No. 70,200

3 Claims. (Cl. 59—79)

1

This invention relates to improvements in expandable metal bands, chains or linkages for use in the manufacture of articles of jewelry such as bracelets, necklaces, girdles and the like.

In general, the present invention consists in a series of outer and inner links or chain-elements which are interconnected to flex in relation to each other and having the inner links telescopically slideable in the outer links to permit expansion of the band or bracelet while being normally contracted by means of tension-springs enclosed within the link-elements.

One object of the invention is to provide an improved article of manufacture of the type indicated in which the link-elements are adapted to be more conveniently and rapidly assembled and the springs applied thereto through the use of interfitting parts to hold them at the end.

Another object is to provide an article of the type indicated which is economical to manufacture, of stronger construction and proof against disarrangement of the parts or dislocation of the links when the article is used as an expandible bracelet.

Another object is to provide an improved structure of inner hollow link-elements which may be assembled with their top and bottom portions held together without the use of pins, rivets or solder yet adapted for interconnection in such manner as to prevent their displacement or coming apart.

Another object is to provide an improved structure of the link-elements in which the mechanical parts such as the springs and their holding means are entirely concealed from view to improve the overall appearance of the chain or linkage.

Further objects of the improvements are set forth in the following specification which describes one preferred form of construction of the invention by way of example as illustrated by the accompanying drawing. In the drawing:

Fig. 1 is a side elevational view of a bracelet embodying the present improved construction of the link-elements shown with the ends of the linkage attached to a wrist-watch;

Fig. 2 is a greatly-enlarged side elevational view of a series of the connected link-elements of the band or bracelet shown partly in section to illustrate the interior construction of the elements;

Fig. 3 is a similarly enlarged view showing the telescopic elements of the linkage as extended during expansion of the band or bracelet;

Fig. 4 is an enlarged bottom plan view of sev-

eral of the link-elements of the linkage showing the latter as expanded with the link-elements in extended relationship;

Fig. 5 is a still further enlarged end view of the inner telescopic link-element shown partly in section;

Fig. 6 is a similarly enlarged end view showing the inner link-element assembled with the outer link-element and illustrating the cross-pin for anchoring one end of the tension-spring; and

Fig. 7 is an enlarged perspective view of several of the link-elements before interconnected and illustrating one member of the inner sliding element as disassembled from its upper co-operating part with its bottom wall partly broken away.

The flexible band or linkage of the present invention is in some respects similar to that disclosed in my prior pending application Serial No. 729,431, filed February 19, 1947, and consists of improvements in the structure and arrangement of the parts of the inner links to provide more secure attaching means for the springs, and generally a structure which permits more convenient and rapid assembly of the several parts of the inner link-elements. The present improved chain or linkage consists of a series of box-like outer link-elements 2 enclosing inner connecting links 3 which are telescopically slideable therein and normally held in contracted relationship to tension-springs 4 to provide for contraction and expansion of the band or bracelet as a whole.

The outer enclosing links 2 may be constructed from sheet-metal with a top wall 6, preferably arched or crowned laterally across its width, as shown more clearly in Fig. 6, and provided with side walls 7 having portions 8 folded inwardly at right-angles to meet at the center and form a relatively flat bottom wall. At each end of the side walls 7 the metal is extended in a series of relatively narrow lugs 14 and 15 adapted to be bent inwardly to connect the elements of the linkage together in a continuous band or bracelet. In this way the outer or main link-element 2 is shaped in the form of a rectangular tube with a closed top, bottom and sides, but open at both ends to receive the inner sliding link 3.

The inner sliding link-element 3 comprises two separate parts 20 and 21 as shown more particularly in the composite view Fig. 7, it being understood that in this view all the several parts of the links are shown in inverted relationship, that is, bottom side up. The upper part 20 of the link-element 3 is constructed with a top wall

22, preferably arched or crowned across its width to conform to the crowned top of the outer link 2. This part of the link 3 may be constructed of sheet-metal struck up in dies with one end of the blank curled over at 23 and extended in a bottom portion 24 terminating in spaced parallel projections 25-25 forming a slotted recess or opening 27 therebetween. At the opposite end of the member 20 the metal is folded at right-angles to form an end wall 28 formed with a central rectangular opening 29 therein provided for a purpose as later explained. The metal of the end wall 28 is then folded inwardly at 30 in a flat portion which is cut away at the center to form a slotted recess 31 with two projections 32 at its sides.

15 The bottom member 21 of the inner telescopic link-element 3 may be formed of sheet-metal stamped out and shaped in dies to provide a flat bottom wall 33 and upstanding side walls 34, thus having a trough-shape. The bottom wall 33 of the member 21 is cut away at its ends inwardly of the terminal portions of the side walls 34 to provide shouldered ledges 35 and 36 adapted to interfit with the slotted bottom portions 24 and 30 at the ends of the upper member 20 of the inner link 3 in the manner as later more particularly explained.

30 The ends of the side walls 34 of the bottom member 21 are adapted to be engaged by the shouldered ends of a hook-shaped cross-member 40. The cross-member 40 takes the form of a flat bar with shouldered ends 41 and projecting forwardly of the bar is a relatively flat hook 42 constructed integral therewith. The hook 42 is adapted to hook through the loop 46 of the helical tension spring 4, the loop 47 at the opposite end of the spring being attached to the outer box-member 2 in the manner as next explained. For connecting this last-mentioned end of the spring 4 to the outer link 2 a cross-pin 48 may be riveted through holes in its sides 7 for insertion through the loop 47 on the spring. Through these connections the spring 4 is anchored at its opposite ends within the outer and inner link-elements 2 and 3, respectively, to normally maintain them telescoped in contracted relationship as shown in Fig. 2 while permitting their longitudinal extension as illustrated in Figs. 3 and 4 of the drawing.

35 The method of assembling the parts of the inner link-elements 3 and connecting them in articulated relation with the outer link-element 2 is as next explained. Conveniently, the loop 46 at one end of the spring 4 may be engaged with the hook 42 of the anchoring cross-member 40, as shown at the left in Fig. 7, and the member 40 placed across the end of the bottom member 21 by engaging its shouldered ends 41 with the ends of its side walls 34 to enclose the spring therebetween as shown in Figs. 4 and 7. The bottom member 21 is then assembled with the top member 20 of the inner link-element 3 by inserting it in place with the shouldered ledges 35 underlying the bottom portion 24 at one end of the member 20 and the opposite shouldered ledges 36 underlying the bottom wall 30 at its opposite end. This last-described interengagement of the parts may be effected by a "snap" action, the ends 50 of the side walls 34 of the member 21 being slightly inclined as shown in Fig. 7 so that they will slide across the edge of the bottom portion 30 of the member 20 until the ledges 36 engage thereunder; it being understood that the opposite shouldered ledges 35 on

5 the member 21 are first engaged in under the bottom portion 24 of the member 20. When the member 21 is assembled with the member 20 in this manner the edges of its bottom wall 33 at each end thereof will abut the transverse edges of the recesses 27 and 31 in the bottom portions 24 and 30 between the projections 25 and 32 of the member 20. In other words, the ends of the bottom wall 33 of the member 21 will assume an interfitting, close connection with the edges extending between the projections 25 and 32 of the lower portions of the top member 20 to provide a substantially unbroken bottom wall for the inner link-element 3, see Fig. 4.

10 After the parts of the inner link-element 3 have been assembled in the manner explained above this element may be inserted into the end of the outer box-link 2 and the end of the spring 4 connected to the latter by the pin 42. As a convenient method for accomplishing this latter connection a wire formed with a hook at its end may be inserted through the outer link 2 and its hook engaged with the loop 47 at the end of the spring 4 to draw it into place for inserting the pin 48 therethrough. The ends of the pin 48 may then be riveted over to hold it securely in place. It will be understood that the end of the spring 4 formed with the loop 47 projects through the rectangular opening 29 in the end of the member 20. After each inner link-element 3 has been assembled in telescopic relation to its companion outer link 2 in the manner above explained the lugs 14 on the outer link-element may be bent inwardly as shown in Figs. 3 and 4 to limit the sliding movement of the inner link-element 3 relatively thereof and maintain the elements interconnected. In this way the whole series of link-elements may be coupled together to form a continuous chain suitable for use in the manufacture of watch-bands, bracelets, necklaces or the like.

15 It will be observed from the foregoing description that the present improvements in the structure and arrangement of the link-elements provide for very convenient and rapid assembling of the chain or linkage both as regards the interconnection of the top member 20 and bottom member 21 of the inner link-element 3, and during the interconnection of the several link-elements in a chain. It is to be especially noted that the method of connecting the top member 20 and bottom member 21 of the inner link-element 3 eliminates the use of screws, pins, rivets, solder or the like and yet produces a most secure 20 joining of the parts while providing a smooth finished appearance on the bottom of this particular link-element. The snap engagement between the members 20 and 21 results in a secure and permanent smooth connection between the ends of the top member and bottom member without any gaps or projections occurring on the surface. Moreover, the engagement of the cross-member 40 with the ends of the side walls 34 of the bottom member 21 provides for the utmost 25 simplicity in the structure while insuring a permanent connection between these parts without chance of their dislocation since the spring 4 is at all times tensioned sufficiently to hold the parts together.

30 While the present improvements are herein shown as embodied in a preferred form of construction, it is to be understood that certain modifications may be made in the shape and arrangement of the elements of the linkage without departing from the spirit or scope of the in-

vention. Therefore, without limiting myself to the exact structure and arrangement shown and described, I claim:

1. As an improved article of manufacture, a band, chain or linkage comprising a plurality of open-ended box-like outer link-elements having lugs projecting at their ends, inner slideable link-elements each comprising a top plate of sheet-metal with folded ends forming bottom portions, a bottom member for each inner link-element constructed of sheet-metal with a bottom wall and upstanding side walls and said side walls formed at both ends with recessed shoulders, said bottom member assembled with the top member of each inner link by engaging the shoulders in under the bottom portions of the top member, a crossbar formed with a hook and extending across one end of the bottom member in engagement with the edges of its side walls, a spring looped at one end to engage the hook on said crossbar and provided with a loop at its opposite end, said inner slideable link-elements adapted to telescope within the tubular box-members with the lugs at one end of the latter engaging with the end portions of the inner link-elements, means for attaching the loop at one end of the spring to the sides of the outer box-member to normally maintain the inner link telescoped within the outer link.

2. As an improved article of manufacture, a band, chain or linkage for use in jewelry such as bracelets, said linkage comprising a series of inner and outer link-elements, said outer link-elements constructed from sheet-metal in tubular form with lugs projecting from its sides at its open ends, inner link-elements each comprising a top plate curled around at one end and projecting inwardly to provide a bottom portion slotted to form a recess at its end, the opposite end of said top member being folded to provide an end wall with a bottom portion projecting inwardly and slotted to form a recess, a bottom member for said inner link-element formed of sheet-metal with a bottom wall and upstanding side walls, the ends of said side walls being formed with shouldered ledges projecting beyond the ends of the bottom wall, a crossbar formed with a forwardly-projecting hook and notches at the ends of said crossbar adapted to engage the ends of the side walls of the bottom member, a spring having a loop at its end engaged with the hook on the crossbar and a loop at its opposite end, said bottom member assembled with the top member by engaging the ledges at its ends in under the bottom portions of the top member with the ends of its bottom wall abut-

ting the lateral edges of the slots in said bottom portions of the top member, said inner link-element being adapted to telescope within the outer link-element and connected therewith by bending the lugs at the ends of the outer link-element into engagement with the ends of the inner link-element, and a pin extending through the sides of the outer link-element in engagement with the loop at one end of the spring, said spring normally maintaining the inner link-element telescoped within the outer link-element while adapting it to be extended from the end thereof to permit expansion in the length of the linkage.

3. As an improved article of manufacture, a band, chain or linkage for use in articles of jewelry comprising a plurality of interconnected telescopic link-elements constructed of sheet-metal and consisting of outer tubular box-like link-elements open at their opposite ends, inner link-elements constructed from separate sheet-metal members, one member having a top wall folded downwardly at its opposite ends with portions projecting inwardly toward each other to provide relatively short bottom walls, each bottom wall formed with a transverse slot at its end and one end wall formed with an opening, a bottom member having a flat bottom wall and upstanding side walls with the ends of said side walls formed with shouldered ledges projecting beyond the ends of the bottom wall, a crossbar formed with a hook and engaging across the ends of the side walls of the bottom member at one end thereof, a helical spring having loops at its ends with one loop engaged with the hook on the crossbar, the bottom member of said link-element being assembled in permanent connection with its top member by engaging the ledges at its ends in under the bottom portions of said top member with the ends of the bottom wall abutting the edges of the transverse slots in the bottom member and prevented from lateral movement on the top member by the projections at the sides of the slots, said inner link-element being inserted within the outer link-element and connected therewith by the lugs on the latter bent inwardly to engage its end to permit limited sliding movement of the inner link-element, and a cross-pin in the outer link-element engaging the loop at one end of the spring to normally anchor the spring to the outer link-element to adapt it to act to slidably telescope the inner link-element within the outer link-element.

LOUIS EDMOND VALCOURT.
